CLAIM

The ornamental design for an insert for hollow railing support post, as shown and described.

DESCRIPTION

FIG. 1.1 is a top perspective view of the insert for hollow railing support post;

FIG. 1.2 is a bottom perspective view thereof;

FIG. 1.3 is a rear view thereof;

FIG. 1.4 is a front view thereof;

FIG. 1.5 is a right side view thereof;

FIG. 1.6 is a left side view thereof;

FIG. 1.7 is a bottom view thereof; and

FIG. 1.8 is an environmental view thereof.

The broken lines shown in the drawings illustrate environmental structure and form no part of the claimed design.

1 Claim, 8 Drawing Sheets
